SANITARY SHOE LINER

Edward C. Hartnett, Arcadia, Calif., assignor of one-half to Frank Del Conte, Los Angeles, Calif.

Application September 22, 1953, Serial No. 26,906

Term of patent 14 years

(Cl. D7—7)

FIG. 1.

FIG. 2.

To all whom it may concern:

Be it known that I, Edward C. Hartnett, a citizen of the United States, residing at Arcadia, California, have invented a new, original, and ornamental Design for a Sanitary Shoe Liner, of which the following is a specification, reference being had to the accompanying drawing, forming a part hereof.

I claim:

The ornamental design for a sanitary shoe liner, substantially as shown.
